DRAIN TILE BAND

Filed Sept. 1, 1927

By J. H. Harness

Attorneys

UNITED STATES PATENT OFFICE

GLENN F. BUTLER, OF DETROIT, MICHIGAN, ASSIGNOR OF FORTY-NINE ONE-HUNDREDTHIRTY-THREE DREDTHS TO CHARLES L. HAMAN, OF DETROIT, MICHIGAN

DRAIN-TILE BAND

Application filed September 1, 1927. Serial No. 216,879.

This invention relates to means for holding the adjacent ends of drain tiles in alignment, the principal object being to provide a device that will be simple in construction, 5 easily applied and economical to manufacture.

Another object is to provide a device for holding the ends of drain tiles in alignment, preventing dirt from entering the joint between the tiles, and providing passages for 10 the flow of water to such joints.

A further object is to provide a device for holding the adjacent ends of drain tiles in alignment comprising a band of metal 15 adapted to surround the adjacent ends of tiles in over-lapping relationship with respect to the joint between the same and formed to provide passages between the band and the tile for carrying water to such joint.

20 The above being among the objects of the present invention, the same consists in certain features of construction and combinations of parts to be hereinafter described with reference to the accompanying drawing, and 25 then claimed, having the above and other objects in view.

In the accompanying drawing which shows a suitable embodiment of the present invention and in which like numerals refer to 30 like parts throughout the several different views,—

Fig. 1 is a side elevation of a pair of drain tiles, the ends of which are held in alignment by the device of the present invention.

35 Fig. 2 is a sectional view taken on the line 2—2 of Fig. 1.

Fig. 3 is an enlarged sectional view taken on the line 2—2 of Fig. 1, showing the manner in which the ends of the band are secured together about the tile.

40 Fig. 4 is a plan view of the band.

Fig. 5 is a perspective view of the band tipped up to disclose the corrugated form of the same.

45 Fig. 6 is a plan view of a modified form of the end construction for the band illustrated in the preceding figures.

Fig. 7 is a fragmentary sectional view 50 taken on the line 7—7 of Fig. 2 illustrating

the method of application of the modified construction shown in Fig. 6.

Fig. 8 is a fragmentary sectional view taken as on the line 2—2 of Fig. 1 showing the application of the modification shown in 55 Fig. 6.

Fig. 9 is an enlarged sectional view taken on the line 9—9 of Fig. 4 illustrating the manner in which the end of the band member is preferably formed.

Fig. 10 is a sectional view as on the line 2—2 of Fig. 1 showing a modified form of band construction.

In the use of drain tiles it is a frequent occurrence to find that the adjacent ends of the tiles are out of alignment, thus having permitted earth to enter the interior of the tiles and plug the same. When such condition has occurred, it is invariably necessary to dig up the tiles, clean them out and replace them, 65 which operation entails considerable time, labor and expense. Such misalignment invariably occurs when the tiles are first laid or shortly thereafter on account of the earth not being properly tamped whereby upon 70 back-filling or consequent settling of the earth the tiles move and get out of their respective aligned positions. It also often occurs that the tiles are not fitted together properly when laid with the result that an abnormal space is left between the same through 75 which earth may find its way and eventually plug the tiles.

By the present invention I provide a device 80 which eliminates misalignment of the tiles and prevents the earth from finding a free 85 passage through the joints between the tiles. As illustrative of the present invention I show in the accompanying drawing a pair of tiles 15 and 16 in axial alignment and having their ends in substantially abutting relationship but spaced sufficiently from each other so that the joint 17 between the same affords a passage for water from the exterior to the interior of the tiles. Surrounding the 90 ends of the tiles 15 and 16 over the joint 17 is a strip of material 18 incorporating the present invention. As best shown in Figs. 4 and 5, this strip which is preferably made 95 of metal, but may be made of other suitable 100

material, is provided between its ends with a series of corrugations 19, the corrugations 19 extending preferably to adjacent each end thereof. One end of the band is formed to provide a transverse strap 20 extending between the ends above the surface of the strip 18. The opposite end of the strip 18 is cut away to provide an elongated tongue 21, preferably of less width at its outer end than at its inner end and in order to be more readily inserted under the strap 20.

In practice when the tiles such as 15 and 16 are being laid, the strip 18 is placed around the tile over the joint 17 between the same, the tongue 21 is inserted beneath the strap 20, the strip or band 18 is drawn tightly into contact with the tiles 15 and 16, and the end of the tongue 21 projecting through the strap 20 is then reversely bent upwardly and back on itself over the strap 20, thereby locking the band 18 securely in position about the joint 17. It will be apparent that this provides a sleeve in which the adjacent ends of each tile 15 and 16 is socketed, and thereby preventing misalignment of such ends. At the same time it is sufficiently wide to protect the joint 17 from the entrance of earth when the joint 17 is abnormally wide. The corrugations 19 on the underside of the band 18 provide passages leading from the edges of the band 18 to the joint 17 through which water in the earth around the tile may travel and find its way through the joint 17 into the interior of the tiles and be carried away. If desired the tongue 21 may be provided with a plurality of upstanding projections 22, as best indicated in Fig. 9, so that when the tongue 21 is inserted below the strap 20 and the band 18 is drawn tightly about the tiles 15 and 16, the projections 22 will engage the edges of the strap 20 and prevent the band from loosening up until the end of the tongue 21 is bent back to locked position.

If desired tongues or downwardly extending projections may be formed on the strip or band 18 along the center line thereof for reception in the joint 17 in order to prevent any possibility of axial displacement of the band 18 in respect to the joint 17 and thereby expose the joint 17 directly to the earth. The projections may be formed as indicated in Figs. 6, 7 and 8, in which a tongue 23 is shown as struck out of the metal of the band itself and bent inwardly where it is received in the joint 17 between the tiles 15 and 16. I prefer to employ but one projection 23 and to form the same between the strap 20 and the adjacent end of the band 18 so that the opening left in the band 18 by the formation of the projection 23 will be covered by the tongue 21 when it is inserted beneath the strap 20 in securing the band 18 about a joint such as 17. It will be understood, of course, that a plurality of these projections may be employed when desired.

In Fig. 10 I show a further modified form of band construction. The band 24 in that view is of sheet metal similar to the band 18, but instead of being provided with a plurality of corrugations such as the corrugation 19 in the band 18, it is provided with a plurality of projections 25 formed by depressing the outer surface of the band 24 at a plurality of spaced points thereby providing a plurality of points for contact against the tiles 15 and 16 instead of the plurality of lines as in the case of the band 18.

While I have illustrated in the drawing a band corrugated between its ends to provide drainage passages to the joint 17, it will be apparent that such passages are necessary only on the surface of the band which contacts against the tiles and therefore that if grooves are formed in such surface the function of the band will not be impaired in any respect. It will also be understood that although I have shown the present invention in the form of a flexible band, flat in original shape, the same may be made of two or more parts and of rigid construction and joined together in order to accomplish the purpose above described, or it may be originally formed circular in shape and slipped over the tubes, and it will also be understood that when a single flexible strip as shown is employed in the particular method of joining the ends of the same together about the joint 17 and in overlapping relationship with respect thereto is immaterial as far as the present invention is concerned, and any suitable method for securing such ends together may be employed.

Formal changes may be made in the specific embodiment of the invention described without departing from the spirit or substance of the broad invention, the scope of which is commensurate with the appended claims.

What I claim is:

1. A device for holding the adjacent ends of drain tiles in alignment comprising a flexible band formed from sheet metal adapted to overlap said joint, said band being formed to provide drain passages between the same and said tiles extending angularly with respect to the length of said band.

2. A device for holding the adjacent ends of drain tiles in matching relationship comprising a flexible band adapted to be bent around said tiles in overlapping relationship with respect to the joint between the same, and being corrugated to provide water passages leading from the edges of said band to said joint.

3. A device for holding the adjacent ends of drain tiles in matching relationship comprising a strip of metal transversely corrugated between its ends and formed to provide a tongue at one end and a strap at the other end, said strip adapted to be placed around said tiles in overlapping relationship in re-

spect to the joint between the same with said tongue received in said strap and reversely bent to prevent dislocation of said strip.

4. A device for maintaining the adjacent ends of drain tiles in alignment comprising a band received about said tiles in overlapping relationship with respect to the joint between the same, drain passages formed in said band for conducting water to said joint, and means for preventing axial displacement of said band.

5. A device for holding drain tiles in alignment comprising a band corrugated between its ends and adapted to fit around the adjacent ends of a pair of tiles in overlapping relationship to the joint between the same, and an inwardly extending tongue on said band adapted to be received in said joint for maintaining said overlapping relationship of said band.

6. A device for holding the ends of drain tiles in alignment comprising a strip of metal provided with a transverse strap at one end and a tongue at the other end, said strip adapted to extend around said tiles in overlapping relationship in respect to the joint between the same, and a projection struck out of the metal of said strip between said strap and the adjacent end of said strip and bent inwardly for reception of said joint, the opening left in said strip by the formation of said projection being covered by said tongue when received by said strap for the purpose of holding said strip in position around said tiles.

7. A device for holding the ends of drain tiles in alignment comprising a strip of metal corrugated between its ends and provided with a transverse strap at one end and an extended tongue at the other end, said strip adapted to be placed about the adjacent ends of a pair of tiles in overlapping relationship with respect to the joint between the same and be held in place by inserting said tongue beneath said strap and bending it back over said strap, said tongue being formed with a plurality of projections on the surface thereof for engagement with an edge of said strap.

50 8. In combination with a pair of axially aligned and substantially abutting drain tiles, a flexible band surrounding said tiles in substantially equally disposed relationship with respect to the joint between the same, said band being transversely corrugated to provide drain passages leading to said joint.

9. Means for holding the adjacent ends of drain tiles in alignment comprising, in combination, a relatively narrow strip of flexible material adapted to encircle the adjacent edges of a pair of aligned tiles, means for securing the free ends of said band together about said tiles, and means for holding at least that portion of the main body of said

band in radial alignment with the joint between said tiles outwardly spaced from the outer surface of said tiles, said band formed to permit the passage of water exterior thereto to said joint.
